of America, a corporation of Delaware

Application June 9, 1944, Serial No. 539,528

3 Claims. (Cl. 250—27)

1

Our invention relates to balanced detectors for altimeters or other distance measuring systems of the frequency modulated or FM type.

In application Serial No. 445,720, filed June 4, 1942, in the name of Royden C. Sanders, Jr., entitled Frequency modulated altimeter or distance indicator, there is described a balanced beat frequency detector comprising diodes and a tuned line in which undesired amplitude modulation in an FM altimeter or radar system is balanced out. The present invention is an improvement on balanced detectors of this type.

An object of the present invention is to provide an improved detector of the balanced type.

A further object of the invention is to provide an improved balanced detector for use in FM distance measuring systems such as altimeters.

A further object of the invention is to provide a detector of the balanced type that can be adjusted to an exact balance with a minimum of difficulty.

A still further object of the invention is to provide an improved balanced detector for centimeter wave signals.

According to one preferred embodiment of the invention the detector comprises a tuned coaxial line and a pair of diodes connected in parallel relation across one end thereof by means of capacitors. The signal from the receiving antenna (which is the signal from a reflecting surface or object) may be applied to the coaxial line whereby this signal is fed to the diodes in parallel relation. The signal direct from the transmitter, which functions as a heterodyning signal, is fed to the diodes in push-pull relation as a result of the following arrangement:

The inner conductor of the coaxial line is split or bifurcated at the end adjacent to the diodes to form a loop or two-wire line which is capacity terminated to function as a resonant line. The heterodyning signal is applied to this split-line loop through a coupling loop positioned adjacent thereto. Since the two diodes are connected to the inner coaxial line conductor at opposite sides of the split-line portion, the result is that the heterodyning signal is applied to them in push-pull relation. The resulting beat frequency signal, which may be either audio or intermediate frequency, is taken from the diodes through a pair of conductors that pass axially through the inner conductor whereby they are properly shielded from the radio frequency signals.

The invention will be better understood from

2

the following description taken in connection with the accompanying drawing in which

Figure 1 is a sectional view of a balanced detector embodying the invention,

5 Figure 2 is a view, partly in section, taken on the line II—II of Fig. 1,

Figure 3 is a sectional view taken on the line III—III of Fig. 1,

10 Figure 4 is a schematic diagram showing the electrical circuit of the detector illustrated in Figs. 1, 2 and 3,

Figure 5 is a simplified circuit diagram showing the audio frequency portion of the circuit illustrated in Fig. 4,

15 Figure 6 is a view taken on the line VI—VI of Fig. 2 showing a double loop for coupling to the split-line loop, and

Figure 7 is a sectional view illustrating a modified structure for the detector shown in Fig. 1.

20 In the several figures, similar parts are indicated by similar reference characters.

Referring to Figs. 1, 2 and 3, the parallel feed portion of the detector comprises a tuned coaxial line consisting of an outer tubular conductor 10 and an inner conductor 11. The inner conductor 11 is a solid rod that has two longitudinal holes 12 and 13 therein through which pass a pair of conductors 14 and 16, respectively.

25 30 An annular spacing and supporting member 17 is provided at the lower end of the coaxial line at which point it short circuits the line. The coaxial line is tuned by a slidable short-circuiting ring 18 that carries flexible contact fingers 19. The ring 18 may be adjusted by means of a pair of rods 21 and 22 that are slidable in the spacer ring 17.

35 40 Signal from the receiving antenna may be applied to the coaxial line 10, 11 through a pair of coaxial conductors 23, 24 as indicated in Fig. 2.

The upper end of the outer conductor 10 is joined to a transverse tubular section 26 into which the upper end of the inner conductor 11 extends. A pair of diodes 27 and 28 of the "light-house" type are supported in opposite ends of the section 26 with their anodes 15 and 20 opposite the inner conductor 11. The anodes 15 and 20 are conductively connected by means of clips 31 and 32 to the conductors 14 and 16, respectively, these conductors being brought outside the inner conductor 11 through holes in the sides of the conductor 11 which join the longitudinal holes 12 and 13.

45 50 For radio frequency signals, the anodes 15 and 20 of the diodes are connected capacitively

through mica spacers 33 and 34 to opposite sides of the inner conductor 11.

Referring now to the push-pull portion of the circuit, the upper end of the inner conductor 11 is split to form a two-wire line or loop 37 that is capacitively terminated, the di-electric for the capacity termination being a piece of mica 36 in the example illustrated. Also, a loading resistor 35 is connected across the split end of conductor 11 to reduce the Q of the push-pull circuit considerably below the Q of the parallel feed circuit. The loop circuit 37 is the portion of the inner conductor 11 that surrounds the rectangular opening or split 37.

The heterodyning signal (the signal direct from the transmitter) is fed to the loop 37 through a loop 41 (Figs. 2 and 4) coupled thereto. In the example shown, the loop 41 is a double loop for improving balance which is described and claimed in application Serial No. 538,052, filed May 30, 1944, in the name of Daniel Blitz, and entitled Balanced detector for altimeters. If preferred, a single loop may be used to couple to the split-conductor loop 37. The flow of heterodyning current around the loop 37 is indicated in Fig. 4 by the arrows.

The upper end of the split-conductor loop 37 is balanced with respect to the transverse tubular member 26 (which, preferably, is grounded) by means of a capacity plate 42 which is eccentrically attached to a rotatable supporting rod 43. Thus, the anodes 15 and 20 at a given instant are above and below ground potential, respectively, by a like amount. It will be apparent that this is the desired push-pull application of the heterodyning signal to the diodes 27 and 28.

The diodes 27 and 28 are supported in tubular members 46 and 47, respectively, by means of supporting rings 48 and 49. The tubular members 46 and 47 are fastened to the tubular member 26 in coaxial relation therewith by means of threaded clamping rings 51 and 52, respectively. The supporting rings 48 and 49 have flexible-finger contact rings 53 and 54, respectively, mounted thereon. The contact rings 53 and 54 are insulated from their supporting rings 48 and 49 by means of mica washers 56 and 57 as illustrated.

The fingers of the contact rings 53 and 54 are in contact with the diode metal wall sections which are connected to the diode cathodes 58 and 59 (Figs. 4 and 5). Thus the cathodes 58 and 59 are connected at radio frequencies to the tubular section 26 through capacitors 61 and 62 (Fig. 4) which have the washers 56 and 57 (Fig. 1) as the dielectric.

Before discussing in more detail the electrical circuit of the balanced detector, the double coupling loop 41 will be described with particular reference to Figs. 2 and 6. The two loops 41 are supported by a block 63 of insulating material and, as shown in Fig. 2, are positioned above the split conductor section 37. The loops 41 are covered by a rectangular shielding can 65 that is attached to the tubular section 26.

As shown in Figs. 4 and 6, one of the loops 41 is connected through a resistor 66 to one side of the input line 67; the other end of this loop is connected to the shielding can 65. Likewise, the other loop 41 is connected through a resistor 68 to the other side of the line 67; and the other end of this loop is connected to the shielding can 65. The line 67 preferably is of a type having

considerable loss whereby proper termination of the line is less critical.

The transmitter end of the line 67 is grounded at a point 69 for insuring balanced excitation of the line 67 from the transmitter and hence balanced excitation of the detector. However, grounding the transmitter end of the line 67 does not always eliminate all signal due to unbalance excitation for the reason that the grounded point 69 is not always exact as to location. It is because of this that the double loop 41 is employed. It will be apparent that the coupling to the detector loop 37 from any part of the double loop 41 will include both sides of the line 67 and any current difference will be averaged out.

Figs. 4 and 5 are schematic diagrams which show more clearly the electrical circuit of the balanced detector, Fig. 5 being a diagram of the audio frequency portion of the circuit only. The radio frequency portion of the circuit, with its push-pull and parallel modes of operation, has been fully described. The audio or beat frequency portion of the circuit may include two transformer primary windings 71 and 72 which receive signal from the diodes 27 and 28, respectively, and which are connected in opposing relation. A secondary coil 73 supplies the audio signal to a frequency counter or other utilization circuit (not shown).

One end of the primary 71 is connected to the anode 15 through a resistor 74 which together with the capacity indicated at 76 acts as a radio frequency filter. The other end of the primary 35 71 is connected through a conductor 75 to the cathode 59 which is held at ground potential by a large electrolytic capacitor 79. Also, one end of the primary 72 is connected to the anode 20 through a resistor 77 which together with the capacity indicated at 78 acts as a radio frequency filter. The other end of the primary 72 is connected through a conductor 81 and a loading and self-biasing resistor 82 to the cathode 58 which is grounded through a cathode pin and 45 a socket (not shown). The resistor 82 is bypassed for the beat frequency by a filter capacitor 83.

It will be noted that the diodes 27 and 28 are in series for direct current but are in parallel 50 for the beat frequency signal. The D.-C. voltage drop across the resistor 82 opposes current flow due to contact potential at the diodes.

It will be understood that any signal due to amplitude modulation at the detector will be 55 in phase at the anodes 15 and 20 and therefore will be balanced out in the transformer 71, 72, 73. The beat frequency signal, on the other hand, will be 180 degrees out of phase at the anodes 15 and 20 whereby the beat frequency 60 outputs of the two diodes will add and appear in the secondary 73.

Fig. 7 illustrates a different method of coupling from the transmitter to the two-wire line or loop 37. In this case the coupling is made by a pair 65 of conductors 86 and 87 that extend through two additional longitudinal holes 88 and 89 in the inner conductor 11. The conductors 86 and 87 have resistors 91 and 92, respectively, in series therewith for terminating the line 67.

The conductors 86 and 87 are cross-connected to oppose sides of the loop 37 at the junction of the comparatively wide upper portion 37a and a comparatively narrow lower portion 37b. Thus the output of the line 67 is connected across the 75 portion 37b of the complete loop 37, the impe-

dance of this portion being a comparatively small percentage of the total loop impedance because of the narrowness of the slot forming the portion 37b.

It will be evident that the coupling into the loop 37a, 37b is due to the current flow from the conductor 86 down one side of the loop portion 37b, up the other side of loop portion 37b and into the conductor 87 as indicated by the arrows.

The loop 37 is in quarter wave length resonance. If properly excited and loaded, the potential on the capacitive end of the loop 37 will be symmetrical to ground. The slot forming 37b is made narrow so that the potential distribution on the loop 37 will remain practically symmetrical regardless of unbalance of the energy in the direct coupling lines 67.

The termination of each of the coaxial lines formed by the center conductors 86 and 87 and by the associated outer conductors consisting of the walls of the holes 88 and 89, respectively, is in the loop 37b. The electrical center of each coaxial line termination is not in the center of the lower end of the slot 37b but is displaced by an amount approximately equal to the amount that the center conductor extends beyond the upper end of its outer conductor. Therefore, for maximum inherent symmetry the slot 37b should be made as narrow as mechanical limitations permit.

We claim as our invention:

1. A balanced detector comprising a tuned coaxial line having an outer conductor and an inner conductor, said inner conductor having an end section that is bifurcated and capacity terminated to form a tuned two-wire line section, a pair of rectifiers, one rectifier being connected between said outer conductor and one side of said bifurcated section, the other rectifier being connected between said outer conductor and the other side of said bifurcated section, means for applying signal to said coaxial line, said signal lying within the frequency range to which said coaxial line is tuned, means for simultaneously applying signal to said two-wire line section, said last signal lying within the frequency range to which said two-wire line section is tuned, and means for supplying from said diodes to a utilization circuit any beat frequency signal resulting from an instantaneous frequency difference of said signals.

2. A balanced detector comprising a tuned coaxial line having an outer conductor and an inner conductor, said inner conductor having an end section that is bifurcated and capacity terminated to form a tuned two-wire line section, a pair of rectifiers, one rectifier being connected between said outer conductor and one side of said bifurcated section, the other rectifier being connected between said outer conductor and the other side of said bifurcated section, means for applying signal to said coaxial line, said signal lying within the frequency range to which said coaxial line is tuned, means for simultaneously applying signal to said two-wire line section, said last signal lying within the frequency range to which said two-wire line section is tuned, and means for supplying from said diodes to a utilization circuit any beat frequency signal resulting from an instantaneous frequency difference of said signals, said last means including a pair of conductors that pass through two longitudinal holes in said inner conductor and which are connected to an electrode of each of said diodes, respectively.

3. The invention according to claim 2 wherein said last means includes a transformer having two primary windings and a secondary winding and wherein said pair of conductors are connected to supply diode current to said two primary windings, respectively.

4. A balanced detector comprising a tuned coaxial line having an outer conductor and an inner conductor, said inner conductor having an end section that is bifurcated and capacity terminated to form a tuned two-wire line section, a pair of rectifiers each having an anode and a cathode, one rectifier having its cathode connected through capacity to said outer conductor and having its anode connected through capacity to one side of said bifurcated section, the other rectifier having its cathode connected through capacity to said outer conductor and having its anode connected through capacity to the other side of said bifurcated section, means for applying signal to said coaxial line, said signal lying within the frequency range to which said coaxial line is tuned, means simultaneously for applying signal to said two-wire line section, said last signal lying within the frequency range to which said two-wire line section is tuned, and means for supplying from said diodes to a utilization circuit any beat frequency signal resulting from an instantaneous frequency difference of said signals, said last means including a pair of conductors that pass through two longitudinal holes in said inner conductor and which are connected to an electrode of each of said diodes, respectively.

5. The invention according to claim 4 wherein said last means includes a transformer having two primary windings connected in opposing relation and having a secondary winding connected to said utilization circuit and wherein said pair of conductors are connected to supply diode current to said two primary windings, respectively.

6. A balanced detector comprising a tuned coaxial line having an outer conductor and an inner conductor, said inner conductor having an end section that is bifurcated and capacity terminated to form a tuned two-wire line section, a pair of rectifiers each having an anode electrode and a cathode electrode, one rectifier having one of its electrodes connected through capacity to said outer conductor and having its other electrode connected through capacity to one side of said bifurcated section, the other rectifier having one of its electrodes connected through capacity to said outer conductor and having its other electrode connected through capacity to the other side of said bifurcated section, means for applying signal to said coaxial line, said signal lying within the frequency range to which said coaxial line is tuned, means comprising a loop adjacent to said two-wire line section for applying signal thereto, said last signal lying within the frequency range to which said two-wire line section is tuned, and means for supplying from said diodes to a utilization circuit and beat frequency signal resulting from an instantaneous frequency difference of said signals, said last means including a pair of conductors that pass through two longitudinal holes in said inner conductor and which are connected to an electrode of each of said diodes, respectively.

7. A balanced detector comprising a tunable coaxial line having an outer conductor and an inner conductor, said inner conductor having an end section that is bifurcated and capacity terminated to form a tuned two-wire line section,

a pair of rectifiers, one rectifier being connected between said outer conductor and one side of said bifurcated section, the other rectifier being connected between said outer conductor and the other side of said bifurcated section, means for applying signal to said coaxial line, said signal lying within the frequency range to which said coaxial line is tuned, means for simultaneously applying signal to said two-wire line section, said last signal lying within the frequency range to which said two-wire line section is tuned, said last means comprising a pair of conductors that pass through two longitudinal holes in said inner conductor and which are cross-connected to opposite sides of said bifurcated section, and means for supplying from said diodes to a utilization circuit any beat frequency signal resulting from an instantaneous frequency difference of said signals.

8. A balanced detector comprising a tuned coaxial line having an outer conductor and an inner conductor, said inner conductor having an end section that is bifurcated and capacity terminated to form a tuned two-wire line section, a pair of rectifiers each having an anode electrode and a cathode electrode, one rectifier having one of its electrodes connected through capacity to

said outer conductor and having its other electrode connected through capacity to one side of said bifurcated section, the other rectifier having one of its electrodes connected through capacity to said outer conductor and having its other electrode connected through capacity to the other side of said bifurcated section, means for applying signal to said coaxial line, said signal lying within the frequency range to which said coaxial line is tuned, means for simultaneously applying signal to said two-wire line section, said last signal lying within the frequency range to which said two-wire line section is tuned, said last means comprising a pair of conductors that pass through two longitudinal holes in said inner conductor and which are cross-connected to opposite sides of said bifurcated section, and means for supplying from said diodes to a utilization circuit any beat frequency signal resulting from an instantaneous frequency difference of said signals, said last means including a second pair of conductors that pass through two longitudinal holes in said inner conductor and which are connected to an electrode of each of said diodes, respectively.
